Inventor

WILLIAM HICKS,

By his Attorney

W. L. Lewis.

UNITED STATES PATENT OFFICE.

WILLIAM HICKS, OF DANVILLE, KENTUCKY, ASSIGNOR OF ONE-HALF TO
EDWARD B. RUSSEL, OF SAME PLACE.

HEMP-BRAKE.

SPECIFICATION forming part of Letters Patent No. 409,102, dated August 13, 1889.

Application filed August 27, 1888. Serial No. 283,863. (No model.)

To all whom it may concern:

Be it known that I, WILLIAM HICKS, a citizen of the United States, and a resident of Danville, in the State of Kentucky, have 5 invented a new and useful Improvement in Hemp-Brakes, of which the following is a specification.

This invention relates to improvements in the construction of hemp-brakes such as are 10 adapted to be carried from shock to shock and to be singly worked by hand; and it consists, primarily, in making the central vertical blade or sword a curved blade, and at the same time higher than the other blades 15 of the bed-frame, which adapts a given weight of brake to clean a given quantity and quality of hemp better and faster as compared with the old-style hand-brake having a straight center blade.

20 The present invention consists, further, in an upper frame having curved blades with their principal concavity in front, and a straight handle at its front edge, in combination with a bed-frame having its curved blades correspondingly arranged, whereby the operator is enabled to grasp the handle with equal 25 facility at any point in braking long and short hemp.

A sheet of drawings accompanies this specification as part thereof.

Figure 1 of the drawings represents a top view, and Fig. 2 a front view, of a hemp-brake illustrating this invention. Fig. 3 represents a cross-section on the line 3 3, Fig. 1.

35 Like letters of reference indicate corresponding parts in the several figures.

The "bed-frame," as it has been termed, of this improved brake is conveniently supported by a corner-post A and three legs B 40 B², attached to long and short end pieces C C², with said corner-post at the right-hand end in front. Between the extended upper end of said post A and a short post A², erected on said end piece C, the upper frame of the 45 brake is pivoted by trunnions x on the extremities of an end piece D. At its left-hand end a short end piece D² rests normally upon said end piece C².

The features above referred to are custom-

ary and preferred details which form no part 50 of the present invention.

The opposing upper and lower swords or blades and handle to which this invention relates are constructed and arranged as follows: The upper blades a a are curved blades 55 of the customary ogee shape, with their principal concavities in front and a wide central space between them. This space accommodates a curved center blade b in the bed-frame, which is of like ogee shape, and which 60 is fixedly supported by said end pieces C C², together with lower or less prominent back and front blades b² b³. Of these the former is curved correspondingly with the center blade, and the front blade b³ is straight, extending at right angles from the end piece C to the end piece C². One or more tie-pieces t, extending from front to back beneath the blades b b² b³, and attached to their lower edges, may aid the curved center 65 blade to resist the greater strain to which it is subjected. A straight handle h extends from near the front end of said end piece D to the middle of the short end piece D² at the left-hand end of the brake, and is thus 70 substantially parallel with said straight front blade b³.

The improved brake is used like other hand-brakes, except that the center blade b, being a curved blade and more prominent 75 than the back and front blades b² b³, and at the same time available for short and long hemp alike at its respective ends, increases the efficiency of the brake, owing to the greater length of center blade so afforded in 80 a brake of given dimensions; and the handle h, being located close to the straight front and parallel therewith, is easily reached by the operator from any position.

Details which have not been specified may 85 be of any approved description; and I do not limit my respective claims to details of construction, except as therein expressly stated.

Having thus described said improved hemp-brake, I claim as my invention and 90 desire to patent under this specification—

1. An improved portable hand-brake having a longitudinally-curved center blade, in

connection with back and front blades of less height, together with opposing curved blades alternating with said center blade, substantially as hereinbefore specified.

5. 2. A pivoted upper frame having a straight handle near the front of the brake and parallel therewith, together with longitudinally-curved blades of ogee shape, having their

principal concavities in front, in combination with a bed-frame having curved center and side back blades correspondingly arranged, substantially as hereinbefore specified.

WILLIAM HICKS.
